UNITED STATES PATENT OFFICE.

JOSEPH MOSÁNSKÝ, OF HOWELL, NEBRASKA.

TOY.

Application filed August 12, 1921. Serial No. 491,751.

To all whom it may concern:

Be it known that I, JOSEPH MOSÁNSKÝ, a citizen of Czechoslovakia, residing at Howell, in the county of Colfax and State of 5 Nebraska, have invented certain new and useful Improvements in Toys, of which the following is a specification.

This invention relates to certain new and useful improvements in toys and has particular reference to the provision of an improved toy gymnast.

The primary object of the invention is to provide a toy gymnast including a pair of bars loosely connected intermediate their 15 ends by a transverse bar so that the ends of the two bars may swing toward and away from each other, the upper ends of the two bars having a string connecting the same, and a toy figure being suspended from said 20 string in such manner that when the lower ends of the two bars are braced together said figure will be caused to simulate various gymnastic feats, and an imitation trapeze being suitably supported by the upper ends 25 of the two bars directly above the figure in such position as to cooperate with the latter in performing such feats.

Another object of the invention is to provide a gymnast toy of the above kind where- 30 in the suspended toy figure is composed of a body portion with jointed legs and arms and with the string passing through the ends, the trapeze being so disposed as to be engaged by the heel and toe portions of the 35 toy figure whereby various feats of a novel nature may be performed.

With the above general objects in view and others that will appear as the nature of the invention is better understood, the same 40 consists of the novel form, combination and arrangement of parts hereinafter more fully described, shown in the accompanying drawing and claimed.

In the drawing, wherein like reference 45 characters designate corresponding parts throughout the several views,

Figure 1 is a front elevational view of a toy gymnast constructed in accordance with the present invention, and

50 Figure 2 is a substantially central vertical sectional view of the device shown in Fig. 1.

Referring more in detail to the drawing, the present device includes a pair of bars 5 which may be constructed of light wood and 55 which are connected intermediate their ends by a transverse bar 6 in such manner that

the ends of the bars 5 may tilt toward or away from each other. This is preferably accomplished by reducing the ends of the bar 6 and passing said ends through openings with arcuate walls as indicated at 7, in the bars 5. The ends of the bar 6 may be held in the openings 7 in any desired manner, and the lower portions of the bars 5 may be conveniently formed as handles to be 60 grasped by the hand.

One or more human figures 8 having loosely jointed legs and arms are supported by the bars 5 through the instrumentality of strings 9 which pass through the ends of the 70 figure or figures 8 and have their ends secured to the upper ends of the bars 5. The strings 9 are so arranged that they will be crossed when the figure or figures hang with extended arms below said strings. When two figures are employed as shown, the strings 9 are preferably crossed between the figures and between the arms of the figures.

A pair of strips 10 of fairly rigid material have their lower ends rigidly attached 80 as at 11 to the upper ends of the bars 5 so that said strips 10 extend substantially parallel with the bars 5 beyond the upper ends of the latter, and the upper ends of the strips 10 are connected by a transverse rod 85 12 upon which one or more trapeze 13 are pivoted, the number of trapeze corresponding to the number of figures 8 and one figure being aligned with each trapeze. The trapeze 13, when a plurality of the same are employed, are located so as to permit engagement of the toe or heel portions of the figure 90 8 therewith with respect to the particular figure disposed therebeneath as indicated by dotted lines in Fig. 2 and various other ways 95 to indicate a person hanging by his toes or heels and a novel and amusing set of gymnastic feats will be imitated to the satisfaction and general amusement of the operator.

By pressing the lower ends of the bars 5 100 together, the upper ends of said bars are spread apart and the strings are thereby caused to straighten out, thus causing a change of the position of the toy so that the gyrations produced will cause the figure or 105 figures 8 to execute many ludicrous antics.

While there is herein shown and described the preferred embodiment of the present invention, it is nevertheless to be understood that minor changes may be made therein 110 without departing from the spirit and scope thereof as claimed.

What is claimed as new is:—

In a gymnastic toy, the combination with a pair of bars tiltably connected at a point between their ends so that the ends of the 5 bars may swing toward and away from each other and have a figure suspended from the upper ends of the same whereby pressing of the lower ends of the bars together and releasing them will cause shifting of the 10 figure, of a trapeze supported by the upper ends of the bars and spaced a suitable dis-

tance above said figure for cooperation therewith, the trapeze support comprising a horizontal bar secured between the upper ends of strip members carried by the adjacent upper ends of the said tilttable bars and running parallel therewith, the said trapeze being loosely retained upon the horizontal bar.

In testimony whereof I affix my signature. 20

JOSEPH MOSÁNSKÝ.
